(57) **CLAIM**

The ornamental design for a sofa, as shown and described.

DESCRIPTION

FIG. 1 is a front perspective view showing the new design;
FIG. 2 is a rear perspective view thereof;
FIG. 3 is a front and left side perspective view thereof;
FIG. 4 is a rear and right side perspective view thereof;
FIG. 5 is a left side perspective view thereof; the right side perspective view is a mirror image of this view and has therefore been omitted;
FIG. 6 is a top perspective view thereof; and,
FIG. 7 is a bottom perspective view thereof.
